Primary Examiner — Elizabeth A Albert(74) *Attorney, Agent, or Firm* — Tim Tingkang Xia, Esq.; Locke Lord LLP(57) **CLAIM**

The ornamental design for an electronic hookah bowl, as shown and described.

DESCRIPTION

FIG. 1 is a front elevation view of a first embodiment of an electronic hookah bowl showing my new design, the rear, right side and left side elevation views being identical to the front elevation view;

FIG. 2 is a top plan view thereof;

FIG. 3 is a bottom plan view thereof;

FIG. 4 is a first perspective view thereof;

FIG. 5 is a second perspective view thereof;

FIG. 6 is a front elevation view of a second embodiment of the electronic hookah bowl showing my new design, the rear, right side and left side elevation views being identical to the front elevation view;

FIG. 7 is a top plan view thereof;

FIG. 8 is a bottom plan view thereof;

FIG. 9 is a first perspective view thereof; and,

FIG. 10 is a second perspective view thereof.

The broken lines shown in the drawings are included for the purpose of illustrating environmental structure and form no part of the claimed design.
